UNITED STATES PATENT OFFICE

171,293

GUIDED MISSILE

William Hunter A. Boyd, Kensington, Md.

Application May 6, 1949, Serial No. 2,503

Term of patent 3½ years

(Cl. D71—1)

To all whom it may concern:

Be it known that William Hunter A. Boyd, a citizen of the United States of America, and a resident of Kensington, Montgomery County, Maryland, has invented a new, original, and ornamental Design for a Guided Missile, of which the following is a specification, reference being had to the accompanying drawings, forming a part hereof.

Fig. 1 is a perspective view of a guided missile as it appears when seen obliquely from above and at the rear;

Fig. 2 is a perspective view of the guided missile as it appears when seen almost directly from the rear;

Fig. 3 is a perspective view of the guided missile as it appears when seen obliquely from above at the front, and

Fig. 4 is a side elevation of the guided missile.

The design for a guided missile is characterized by the tandem arrangement of the body components thereof; the mergence of the diminuent aft portion of the leading component with the bulbous fore portion of the trailing component, and disposition of the tapered, swept-back wings and tail from the respective fore and aft components.

What is claimed is:

The ornamental design for a guided missile, substantially as shown and described.

WILLIAM HUNTER A. BOYD.
